FUEL INJECTION SYSTEM

Filed July 28, 1924

INVENTOR.
Louis O. French

UNITED STATES PATENT OFFICE.

LOUIS O. FRENCH, OF MILWAUKEE, WISCONSIN.

FUEL-INJECTION SYSTEM.

Application filed July 28, 1924. Serial No. 728,805.

The invention relates to fuel injection systems.

The general object of the invention is to provide a fuel injection system for injection-type engines in which the quantity of fuel and the time it is furnished to the engine may be accurately controlled.

In systems of this kind it is not always feasible from the standpoint of efficient operation and maintenance to operate the fuel injection valve electrically. From the operation standpoint it will be appreciated that in some instances there is a disadvantage in providing electrical energy for operating the fuel injection valve when both the fuel pressure and the varying pressures in the cylinder have to be taken into consideration. From a maintenance standpoint it is to be noted that in order to operate a valve electrically with a minimum expenditure of energy, the adjustment of the valve relative to its operating magnet should be carefully maintained so as to keep the air gap at a proper working efficiency. Such adjustments for efficient electrical operation may not be readily maintained in the hands of unskilled persons if applied to a fuel injection valve because, as is quite frequently the case, this valve has to be taken apart for cleaning, resetting or regrinding, or because of clogging of the nozzle by deposits from the cylinder, with a consequent necessity for readjustment. The object, therefore, of this invention, is to provide a fuel injection system in which an electrically-operated control valve, distinct from the outlet valve or fuel injector valve, will operate for long periods of time without any attention and with a minimum expenditure of electrical energy for its efficient operation and will control the operation of the fuel injector.

A further object of this invention is to provide a fuel injection system for multi-cylinder engines in which the fuel, at substantially constant pressure in a supply pipe, is furnished to automatically-operable fuel injection valves whose operations are under the control of electrically-operated control valves.

Where the fuel injection valve is so arranged with reference to the combustion chamber and the cylinder head that it is liable to become highly heated during the operation of the engine, there is an advantage in the system hereinafter described in

the separate electrically-operated control valve since the possible danger of the overheating or destruction of the insulation of the energizing coil is thereby prevented.

The invention further consists in the several features hereinafter set forth and more particularly defined by claims at the conclusion hereof.

In the drawings: Fig. 1 is a view partly in diagrammatic form, of a fuel injection system embodying the invention, parts being shown in section;

Fig. 2 is a vertical sectional view through one of the control valves shown in Fig. 1;

Fig. 3 is a vertical sectional view through the switch mechanism used in the system;

Fig. 4 is a detail sectional view taken on the line 4—4 of Fig. 3;

Fig. 5 is a detail sectional view taken on the broken line 5—5 of Fig. 4.

Referring to Fig. 1, the numeral 6 designates a fuel supply tank, 7 a pump connected with the tank by a pipe 8 and driven by the engine being supplied with fuel and being preferably a double-acting pump or one which will insure a steady flow of fuel to the pressure pipe or line 9. It will be understood that a suitable fuel strainer is provided in the tank or incorporated in the pump or may be used in the supply line for the pump. The pressure in the line 9 may be maintained substantially constant and of a predetermined value in any of the well-known ways and for the purpose of illustration I show a pressure valve 10 of any suitable construction loaded to the desired amount to maintain a pressure head of fuel in the line 9 of the desired value. From the valve 10 some of the fuel may pass through a pipe 11 back to the supply tank. Leading from the discharge pipe 9 are branch pipes 12 and 13 which conduct the fuel to the control devices 14 and then by pipes 15 to the fuel injectors, of the automatic type and one of which 16 is shown in section in connection with the pipe 12. As here shown the injector 16 includes a casing 17 mounted in the head 18 of one of the cylinders of the engine and having a discharge nozzle 19 at its lower end through which fuel passes to the combustion chamber or a chamber in communication with the combustion chamber, the passage of fuel through a duct 20, communicating with pipe 15, to said nozzle being controlled by a check valve 21 nor-

105

115

mally held closed by a spring 22 and the pressure on the head of the valve, the valve being opened by the fuel pressure. With the present system each cylinder of a multi-cylinder engine has its injector supplied with fuel from a branch pipe of the pressure line and the supply to each injector is controlled by the control device 14.

The control device, shown in detail in Fig. 2, includes a tubular casing 23, the upper end of which is closed off by the core 24 of an electromagnet 25 by a suitable threaded and fuel-tight connection therewith. The spool 26 of the magnet carrying the coil 27 is mounted on the top of the casing. A complete valve assembly fits within the casing 23 and closes off its lower end, and is clamped thereto by an annular nut 28 in threaded engagement with the lower end of said casing. This valve assembly or unit includes a valve guide member 29, a valve seat member 30, a valve 31 and a spring 32, said member 30 having an annular flange 33 seating against the lower end of the casing 23 and held thereagainst in a fuel-tight manner by the inwardly extending flange 33 of the nut 28.

The valve guide member 29 is in the form of a tubular cap, fitting for the most part 30 close to the inner wall of the casing and having ports 34, its upper end leading to the chamber 35 formed above it in the casing 23, said cap having a depending stem guide portion 36, an interiorly-threaded portion 37 and a smooth bore portion 38.

The valve seat member 30 is in the form of a screw-plug having a threaded portion 39 engaging the threaded portion 37 of the member and a cylindrical portion 40 fitting 40 closely in the bore 38 so as to center said plug relative to the axis of the guide portion 36. This plug has a passage through it which is tapped at its lower end 41 for a pipe coupling 42 and is of reduced diameter at 43 and has a valve seat 44 at the outlet of the part 43.

The valve 31 is preferably in the form of a needle having its stem guided in the bore of the portion 36, a renewable tip 45 fitting 50 into the lower end of the stem and a spring-seat-flange 46 adjacent the tip, the spring 32 being interposed between said flange and the upper end of member 29. The upper end of the stem is threaded and a disk 47 of magnetic material formed integral with or secured to a sleeve-nut 48 is adjustably mounted on said stem and held in adjusted position by a locknut 49. A pin 50 of non-magnetic material and mounted either in the 55 disk or, as shown, in the core 24, just prevents direct contact between the disk and core to prevent any chance of "freezing". The parts 23, 29 and 30 are of non-magnetic material and the spring 32 may also be of 60 non-magnetic material. It will be noted 65

that the whole valve assembly may be removed as a unit from the casing 23, if necessary.

A tapped outlet 51 from the chamber 35 is adapted to receive a pipe fitting for connecting a pipe, such as the pipe 15, to the fuel injector, which pipe may be made short to minimize the amount of fuel held between the chamber 35 and outlet of the casing 17, and the casing 23 may be directly attached to or formed as a part of the injector casing, so long as the control valve 31 is distinct from the valve 21, and preferably so that the injector valve 21 can be removed without disturbing the adjustment of the valve 31.

With this construction the load imposed by the spring 32 on the valve 31 is such as to hold said valve against its seat against the predetermined fuel pressure in the pipes 12 or 13 and slightly in excess of this pressure. Then when the magnet 25 becomes energized the core 24 attracts the disk 47 and raises the valve off its seat, allowing fuel to pass from the pressure supply to the injector. The electrical energy necessary to raise the valve is that necessary to overcome the excess of spring pressure over the fuel pressure and friction of the parts. The clearance between the disk 47 and the core 95 should be very small so as to permit the magnet to operate at best efficiency. For the usual automotive type engines the total lift of the valve need not be more than a sixtieth to one-hundredth of an inch or less, and the passage 43 should be as small as possible so as to reduce the amount of spring pressure required to close the valve for the particular fuel pressure chosen.

From the foregoing it will be noted that the time of opening the control valve 31 and the duration of its opening will correspondingly effect the injector valve 21 and thereby determine the time of injection and the amount of fuel that is to be furnished to the engine. The time of opening and length of time the valve 31 stays open is determined by the time and duration of energization of the coil 27 of the electromagnet, and this is effected by switch mechanism in the circuit supplying the coil with electrical energy.

Switch mechanism suitable for this purpose and especially for multicylinder engines, is shown in Figs. 3 to 5, inclusive, wherein the numeral 52 designates a tubular support upon which the base plate 53 of the switch casing is rotatably mounted, said plate having a bearing on a flanged collar 54 secured to the support, as by a threaded connection therewith. A shaft 55, driven by the engine has a cam member 56 slidably keyed thereto in any suitable manner, said cam causing the opening and closing of the switch for each of the magnets of the con- 125 130

trol devices. One of said switches is shown in detail and includes the pivoted switch element 57 carrying the contact 58 and the fixed element 59 having the contact 60 adjustably mounted thereon.

The switch element 57 is in the form of a two-armed lever, preferably formed of sheet metal having a channel section except for its ends, and is pivoted on a pin or bolt 61 carried by the ears 62 of a mounting-plate 63 secured to the base-plate 53. One arm of this lever carries the contact 58 and the other is apertured to receive a ball 64, of metal or fibre, which ball is held between said arm and a plate 65 turned over the upper end of said arm and riveted to the arm beneath the ball. This ball is held in operative relation with the cam by a flat curved spring 66 whose free end fits between the sides and bears against the web of the channel of element 57, and whose other end fits into a pocket or recess 67 formed in the plate 63.

The fixed element 59 preferably includes a contact-carrying block 68 welded or brazed to the lateral extensions of a sheet metal channel support 69 within which a part of the contact-carrying arm of the element 57 works. This support 69 has outwardly extending ears 70 through which screws 71 pass within insulated bushings 72 and through mounting-plate 63 into the plate 53, said ears being insulated from the plate 63 by insulation material 73. The lower part of the web of the channel 69 is cut out, as at 74, so that the element 59 is entirely insulated from the plates 53 and 63. A cover 75 of insulating material encloses the switch mechanism and has threaded bushings 76 therein through which contact screws 77 pass into engagement with the back of the fixed contact support 69, said screws having the usual terminal binding nuts 78 thereon for the current supply wires. These screws 77, by their engagement with the supports 69, may also serve to clamp or hold the cover 75 in position on the plate 53. The removal of the cover gives ready access to the entire mechanism of each switch unit.

The cam 56 is cylindrical except for a flattened tapered face portion 79 milled or otherwise formed on it, with one side preferably parallel with the axis of the cam and the other side tapered. The straight or parallel side is preferably the advancing side. When the ball 64 engages the cylindrical surface of the cam the contacts 58 and 60 are held apart and when the flat face 79 registers with the ball 64 the necessary clearance is provided for the lever 57 under the action of the spring 66 to swing toward the cam and cause engagement of the contacts 58 and 60 to close the circuit. Since the flat face 79 is tapered, the varying of the position of this face relative to the ball 64 will vary the time during which the cir-

cuit is closed. Also, since the case 53 carrying the switch or switches can be turned relative to the cam by manual or governor operation of an arm 80 secured to the plate 53, the time the switch or switches start to close can be varied.

The cam 56 may be moved up and down to vary its position by either governor or manually-operated means. As shown, the cam is normally held in a position for an overload fuel charge by a ball 81 centrally mounted in a guide member 82 slidably mounted in a cap 83, clamped to the top of the cover 75, and urged against the cam by a spring 84 interposed between said cap and guide. The lower end of the cam turns on a roller-thrust bearing 85 which is also engaged by a collar 86 provided with pins 87 working in slots (not shown) in the support 52, and engaged by the forked ends of a lever 88 carried by a shaft 89 journaled in a sectional casing 90 secured to said support, said shaft extending outside of the casing and provided on its exposed end with an arm 91 which may be manually or governor actuated. Thus, by the angular adjustment of the switch or switches relative to the cam and the longitudinal adjustment of the cam, the time and duration of energization of the control device or devices may be effected and thus the time of initiating the injection and the amount of fuel injected may be varied to suit the power requirements of the engine. It will also be noted that as the switch unit is radially disposed and its plane of operation radial relative to the cam axis, a number of these units may be compactly arranged about the cam for a multicylinder engine.

The magnets receive current from a battery 92 or other suitable source of electrical energy, one terminal of the battery being shown grounded, as on the engine, in Fig. 1, and the other terminal connected by conductors 93 with one end of the coil of each magnet 25. The other end of the coil of each magnet is connected by a conductor 94 with the fixed contact 60 of the switch mechanism through connection with the screw 77, and the movable contact 58 is grounded through metal plate 53, support 52 to the engine. Cut-out switches 95 in the conductors 94, when opened, prevent further supply of fuel to the engine. A switch 96 may also be provided in each magnet circuit for energizing the magnet to facilitate initial priming of the system.

The initial position of the cam may be such as to provide an overload or priming charge to assist in starting the engine, after which the cam is moved to a position to furnish full or reduced load charges of fuel to the engine.

While the operation of the electromagnet valve 31 is controlled by the switch mechanism, its operation constitutes what may be

termed the sole means for controlling the operation of the injection or outlet valve 21 as distinguished from those systems in which the fuel injector valve is itself mechanically or electrically controlled or operated.

I desire it to be understood that this invention is not to be limited to any particular form or arrangement of parts except in so far as such limitations are specified in the claims.

What I claim as my invention:

1. In a fuel injection system, the combination with a multicylinder engine, of a supply pipe containing fuel at injection pressure, means for supplying said pipe with fuel, branch conduits from said supply pipe leading to each cylinder of the engine, a fuel-pressure-operated injector controlling the passage of fuel from each branch conduit to the cylinder supplied thereby, an electromagnetically-operated valve in each branch conduit and constituting the sole means for controlling the operation of the fuel injector associated with that conduit, a source of electrical current, and circuit control means operated by the engine, for controlling the supply of current to the operating magnet of each electromagnetically-operated valve.
2. In a fuel injection system, the combination with a multicylinder engine, of a supply pipe containing fuel at injection pressure, means for supplying said pipe with fuel, branch conduits from said supply pipe leading to each cylinder of the engine, a fuel-pressure-operated injector controlling the passage of fuel from each branch conduit to the cylinder supplied thereby, an electromagnetically-operated valve in each branch conduit and constituting the sole means for controlling the operation of the fuel injector associated with that conduit, a source of electrical current, and adjustable circuit control means operated by the engine, for controlling the time and duration of current supply to the operating magnet of each electromagnetically-operated valve to thereby control the time and duration of operation of said fuel injector.
3. In a fuel injection system, the combination with the engine and an injector for supplying fuel thereto, of a supply conduit for said injector containing fuel under pressure, an electromagnetically-operated valve in said conduit controlling the supply of fuel to said injector, said valve including a casing, an electromagnet having its core forming a closure for one end of said casing, and a valve

unit extending into the other end of said casing and clamped thereto comprising a needle-valve provided with an armature for said magnet, a guide member for the stem of said valve, a valve-seat member secured to said guide member, and a spring interposed between said guide member and valve.

4. In a fuel injection system, the combination with the engine cylinder, of a fuel injector supplying fuel to the cylinder and having a spring-closed outlet valve opening toward the cylinder, a supply conduit containing fuel under substantially constant pressure and leading to said valve, an electromagnetically-operated valve in said supply conduit constituting the sole means for controlling the operation of said outlet valve, and adjustable engine-operated circuit control means controlling the operation of said electromagnetically-operated valve.

5. In a fuel injection system, the combination of a spring-closed outlet valve for supplying fuel to the engine, a supply conduit containing fuel under substantially constant pressure and leading to said valve, an electromagnetically-operated valve in said supply conduit constituting the sole means for controlling the operation of said outlet valve, and engine-controlled circuit control means controlling the operation of said electromagnetically-operated valve.

6. In a fuel injection system, the combination with the engine cylinder, of a fuel injector supplying fuel to the cylinder and having a spring-closed outlet valve, a supply conduit containing fuel under pressure, a valve casing connected to said conduit, a conduit connecting said valve casing with said fuel injector, a control valve in said casing controlling the passage of fuel to said second named conduit, a spring for normally closing said valve against the fuel pressure in said supply conduit, said control valve being entirely enclosed within said casing and moving within the fuel therein, an electro-magnet associated with said control valve and adapted to exert an attractive force thereon to open it against the excess of spring pressure over the pressure only of the fuel in said supply conduit, means for energizing said electro-magnet, and engine-controlled means for controlling the operation of said energizing means, said outlet valve depending for its opening solely upon the opening of said control valve.

In testimony whereof, I affix my signature.

LOUIS O. FRENCH.
